UNITED STATES PATENT OFFICE.

ANDREW MORRISON, OF PENN TOWNSHIP, ALLEGHENY COUNTY, PENNSYLVANIA, AS
SIGNOR TO DILWORTH, PORTER AND COMPANY, INCORPORATED, OF PITTSBURGH,
PENNSYLVANIA, A CORPORATION OF PENNSYLVANIA.

SLIDE PLATE.

Application filed May 12, 1923. Serial No. 638,502.

To all whom it may concern:

Be it known that I, ANDREW MORRISON, a citizen of the United States, residing at Penn Township, in the county of Allegheny and State of Pennsylvania, have invented a new and useful Improvement in Slide Plates, of which the following is a full, clear, and exact description.

The present invention relates particularly to slide plates for railway switches, and especially to plates of this character having a riser upon which the switch tongue may be moved.

It has heretofore been proposed to produce switch plates of this general construction by rolling in continuous series, and then cutting transversely to provide individual plates. Ordinarily such plates have had a continuous riser which had to be cut away to form seats for the rail and also for the guard rail or rail brace. Such plates have been objectionable from the standpoint of waste metal produced by the milling operation, and from the unnecessary weight of metal handled.

By the present invention there is provided a slide plate constructed to materially reduce the amount of waste metal, and thereby the cost of production and handling.

This invention also has for its object the production of a slide plate adapted to embed uniformly in a supporting tie throughout its entire length, to thereby maintain the desired track conditions without any tilting or spread of the rails.

In the accompanying drawings there are shown for purposes of illustration only certain embodiments of the present invention, it being understood that the drawings do not define the limits of the invention as changes may obviously be made therein without departing from the spirit thereof or scope of my broader claims.

In the drawings:

Figure 1 is a top plan view of a slide plate constructed in accordance with the present invention;

Figure 2 is a side view of the construction illustrated in Figure 1;

Figure 3 is a view similar to Figure 1, illustrating a modified form of slide plate;

Figure 4 is a side view of the construction illustrated in Figure 3;

Figure 5 is a transverse sectional view on the line V—V of Figure 3;

Figure 6 is a top plan view of still another form of slide plate, and

Figure 7 is a transverse sectional view on the line VII—VII of Figure 6.

In the use of slide plates, I have found that the portion of the plate which carries the main track rail is subjected to a greater load than that portion which carries the switch tongue. This difference in loads has heretofore not been taken into consideration in the construction of slide plates, and the result has been a non-uniform embedding of the plates. This places the rails at an inclination and slightly spreads the same, thereby producing undesirable and unsafe track conditions. In accordance with the present invention, the slide plate is designed so as to provide effective tie-engaging surfaces having areas approximately proportionate to the loads which they carry.

Referring more particularly to that form of the invention illustrated in Figures 1 and 2, there is illustrated a slide plate having a rail supporting portion A and a switch tongue supporting portion B. The rail supporting portion is provided with a shoulder 2 adapted to co-operate with one edge of the base flange 3 of a standard track rail. This shoulder is formed of an excess of material adapted to be cut away as may be required to accommodate rails of different sizes. Spaced from the shoulder 2 is a second shoulder 4 preferably slightly higher than the shoulder 2 and adapted to co-operate with one edge of a rail brace 5. The shoulder 4 is formed in a manner similar to the shoulder 2 providing an excess of material adapted to be suitably cut away as may be required to accommodate rail braces of different sizes. It will be understood that in rolling the plate initially the shoulders 2 and 4 are so dimensioned as to co-operate with rails or braces of the smallest dimensions commonly used. With such rail braces no cutting is necessary. The surplus of metal provided in the shoulders, however, makes it possible to cut the shoul-

ders to co-operate with rails and braces of greater dimensions.

The switch tongue supporting portion B is formed with a continuous riser 6 upon 5 which the switch tongue 7 is adapted to slide in moving from one position to the other.

As the load carried by the rail supporting portion is materially heavier than the load carried by the switch tongue supporting portion, 10 the slide plate is preferably rolled to provide an interrupted tie-engaging surface. This may be accomplished by forming a portion of the slide plate base with a depression 8 whereby the switch tongue supporting portion contacts with a tie adjacent the edges 15 only throughout the major portion of its length, while the rail supporting portion has a substantially continuous tie-engaging surface providing a greater area of contact. 20 These respective areas of contact are proportionate roughly to the respective loads carried by the different portions of the plate, thereby insuring a more nearly uniform embedding action which is effective for 25 maintaining the plates in substantially true horizontal position.

It will be understood that the shoulder 9 defining one end of the riser 6 is adapted to co-operate with the opposite base flange 30 3 of a standard rail.

By initially forming the slide plate with spaces 10 and 11 having surfaces substantially flush with the main upper surface of the plate, cutting away at these points is 35 obviated and the weight of metal required for a tie plate is materially reduced. As a further saving of material, the edges of the plate may be cut away or tapered slightly as indicated by the reference characters 12. 40 In order to further insure uniform embedding of the plates in the tie surfaces, the portion of each plate immediately below the shoulder 4 may be cut away by forming a recess 13 similar to the recess 8. Such 45 a construction may be advisable for the reason that the rail brace is not subjected to as great a load as the main rail. This insures a construction in which the resistance to embedding throughout the entire 50 length of the plate bears a definite relation to the loads carried by the different portions of the plate.

The construction described may be produced in quantity and carried in stock irrespective of the particular rail sizes with 55 which the plates are to be used. Conveniently, they may be formed by die rolling to provide a continuous series, the individual plates being later separated by shearing 60 transversely, as is well understood. In certain instances, however, with sufficiently large orders, the plates may be initially rolled to the exact dimensions required for the respective rails and braces with which 65 they are to be used. Such a construction

is illustrated in Figures 3 to 5, both inclusive, in which parts corresponding to the parts already described are designated by the same characters having a prime suffixed thereto. In Figures 3 and 4, the shoulders 70 2' and 4' are of the exact dimensions required. In these figures also the plates are shown as connected in a continuous series 75 adapted to be sheared on the chain lines indicated. It will be apparent more particularly from an inspection of Figure 3 that in the rolling operation, a single recess may provide the interrupted bearing surface for the switch tongue supporting portion and for the rail brace supporting portion. 80

In Figures 6 and 7 there is shown a construction similar to that shown more particularly in Figures 3, 4 and 5 but with straight upper edges. In certain cases, 85 where increased strength is required, such a construction may be provided.

The advantages of the present invention arise from the provision of a slide plate having tie-engaging areas approximately proportionate to the loads which they carry. 90

Further advantages arise from the provision of slide plates having shoulder portions designed to co-operate with rails or rail braces of a minimum size and having an excess of metal which may be cut away to 95 permit co-operation with rails of different sizes.

I claim:

1. A slide plate having on its upper face 100 a rail supporting portion and a switch tongue supporting portion, the lower face of the plate having a greater effective tie-engaging surface per unit of area under the rail supporting portion than at the other portions of the plate at each side of said rail supporting portion, substantially as described.

2. A slide plate having a rail supporting portion and a switch tongue supporting portion, said switch tongue supporting portion having an interrupted tie-engaging face on one side of the rail supporting portion, there being also an interrupted tie-engaging face on the opposite side of the rail supporting portion, substantially as described. 110

3. A slide plate having a rail supporting recess and a switch tongue supporting portion formed during the rolling, said rail supporting recess having shoulders on opposite sides adapted to co-operate with a rail, substantially as described. 120

4. A slide plate having a rail supporting portion and a switch tongue supporting portion, said rail supporting portion having an effective tie-engaging surface of greater area per unit of length than the other tie engaging portions of the plate, substantially as described. 125

5. A slide plate having a rail supporting portion provided with spaced shoulders 130

adapted for co-operation respectively with a rail and with a rail brace, a portion of tie plate below the rail brace engaging shoulder being removed to provide a decreased bearing surface, substantially as described.

6. A continuous plate formed on one side with a riser and with shoulders and on the opposite side with a series of recesses whereby the tie-engaging surface is reduced, said plate being adapted to be cut transversely to form separate slide plates, substantially as described.

7. A continuous plate formed on one side with a riser and with shoulders, and on the opposite side with recesses whereby the tie-engaging surface is reduced, said plate be-

ing adapted to be cut transversely through said recesses to form separate slide plates, substantially as described.

8. A continuous slide plate formed on one side with a riser and with shoulders, and on the opposite side with recesses whereby the tie-engaging surface is reduced, each recess underlying a portion of a riser and a following shoulder, said plate being adapted to be cut transversely intermediate each riser and the following shoulder to form separate slide plates, substantially as described.

In testimony whereof I have hereunto set my hand.

ANDREW MORRISON.
